Patented Apr. 5, 1921.

INVENTOR.
J. R. Morton.

BY

ATTORNEY.

UNITED STATES PATENT OFFICE.

JOHN R. MORTON, OF LEAGUE CITY, TEXAS.

GARMENT-HANGER.

1,374,024.

Specification of Letters Patent.

Patented Apr. 5, 1921.

Application filed September 7, 1920. Serial No. 408,520.

To all whom it may concern:

Be it known that I, JOHN R. MORTON, a citizen of the United States, residing at League City, in the county of Galveston and State of Texas, have invented certain new and useful Improvements in Garment-Hangers; and I do hereby declare the following to be a full, clear, and exact description of the invention, such as will enable others skilled in the art to which it appertains to make and use the same.

This invention relates to a garment hanger, and the object is to provide a device which shall serve the usual purpose, and which when not in use may be folded into compact form, in order that it may readily be placed in a suit case or the like.

A further object is to provide, in a device of the type indicated, a plurality of hingedly connected arms, with certain novel means for bracing the arms when in operative position.

A still further object is to provide, in connection with a plurality of arms hingedly connected, a supporting element retained in position by the closing movement of the arms, and a transverse bracing element for connection with the free ends of the arms.

A still further object is to provide in connection with the construction above outlined, a bracing element comprising a plurality of telescoping devices, with certain novel means for effecting connection between the telescoping elements and the arms of which the device is constructed.

With the foregoing and other objects in view, the invention consists in the novel construction, combination, and arrangement of elements hereinafter described and claimed.

In the accompanying drawings,

Figure 1 is a view of the device in side elevation, the arms being closed and the bracing elements being in position,

Fig. 2 is a view showing the arms swung with reference to each other, and showing the engaging device for the bracing elements thrown to open position,

Fig. 3 is a view of the device in folded position,

Fig. 4 is a detail described below, and Fig. 5 is a sectional view taken on the plane indicated by the line 5-5 of Fig. 2, with the plate in closed position.

In carrying out my invention I employ a plurality of arms 10 and 12 connected by means of a hinge 14, these arms having abutting ends 15 and 16. One end portion 15 is

provided with an aperture 17, and the other end portion is provided with a groove 18, permitting a supporting element 20, which in the present instance is in the form of a hook to be retained in position by the simple operation of throwing the arms into alignment and causing the end thereof to firmly grip the shank of the hook. The shank portion 21 rests within the groove before mentioned, and the offset end 22 is received within the aperture referred to. When the arms are in operative position, that is, in alignment, they are retained by means of a hook 24 engaging a pin 25, the hook being adapted to engage pin 26 when the arms are folded.

A bracing element, comprises a plurality of sections 28 and 29, one of these sections carrying a sleeve 30 receiving the adjacent end of the other section. The extreme ends of the brace are received by sockets in the ends of the arms 10 and 12. Arm 12 is provided with an aperture or socket 31, and the other arm is provided with a socket 33 having communication with an open slot 34, so that the corresponding end of the brace may be received by the socket after the arms 10 and 12 have been thrown into alignment. This socket last named is covered by a pivoted plate 35 pivoted at 35^a having an offset 36 positioned for engagement with the upper wall of the slot to limit the opening movement of the plate. A pin 38 is provided with a head under which the end portion of the plate passes when the latter is thrown to a position for closing the slot and retaining the adjacent end of the brace in position.

Offset 39 limits the movement of plate 35 in the other direction.

When the device is folded into the position shown in Fig. 3, the telescoping sections, detached, are retained against the arms by means of any suitable securing device, such as that shown at 40 in the drawings.

Having thus described my invention what I claim is:

1. In a device of the class described, a plurality of hingedly connected arms, a transverse brace for retaining said arms in an extended position, said brace comprising a plurality of sections detachably connected, each of said arms being formed with a socket for receiving the corresponding end of the brace, and one of the sockets having communication with an entrance slot, and a pivoted plate for closing said slot and retaining the end of the brace within the socket.

2. In a device of the class described, a plurality of hingedly connected arms, a brace for retaining said arms in an extended position, one of the arms being provided with a 5 socket having an open side for receiving the corresponding end of the brace, a pivoted plate for closing said open portion of the socket, an offset formed on the edge of the plate for engaging one wall of the socket 10 and limiting the movement of the plate, and a device for retaining the plate in position for closing the socket and retaining the brace therein.

3. In a device of the class described, a plurality of hingedly connected arms, each of 15 said arms being provided with a socket near its free end and on the inner side thereof, the

socket extending in the direction at an acute angle with reference to the longitudinal axes of the respective arms, and one of said arms 20 being cut away to provide an open entrance slot having communication with the socket, and a transverse brace adapted to be thrust longitudinally into one of said sockets, and to be inserted in the other socket by lateral 25 movement through the open slot, and a pivoted plate for closing said open slot and retaining the brace within the adjacent socket.

In testimony whereof I affix my signature in presence of two witnesses.

JOHN R. MORTON.
